(57) **CLAIM**

The ornamental design for an infant support pad, as shown and described.

DESCRIPTION

FIG. 1 is a top perspective view of an infant support pad showing my new design;

FIG. 2 is a bottom perspective view thereof;

FIG. 3 is a top view thereof;

FIG. 4 is a bottom view thereof;

FIG. 5 is a front side view thereof;

FIG. 6 is a rear side view thereof;

FIG. 7 is a left side view thereof, the right side view being a mirror image thereof; and,

FIG. 8 is a cross-sectional view thereof along center line 8-8 in FIG. 3.

The broken lines illustrate portions of the infant support pad that form no part of the claimed design.

1 Claim, 6 Drawing Sheets
